UNITED STATES PATENT OFFICE.

SAMUEL C. RODESS, OF NEW YORK, N. Y.

SIGNAL HORN.

Application filed August 16, 1922. Serial No. 582,156.

To all whom it may concern:

Be it known that I, SAMUEL C. RODESS, a citizen of the United States, and resident of New York, in the county of New York and State of New York, have invented certain new and useful Improvements in Signal Horns, of which the following is a specification.

My invention relates to improvements in signal horns of the variety embodying a diaphragm and an actuator to engage a stud on the diaphragm to vibrate the latter to produce the desired signals. The actuator of such signal horns are usually operated by means of an electric motor, so far as I am aware.

The object of my invention is to provide means for operating the diaphragm actuator of horns of the class referred to by means of gas pressure and exhaust from an internal combustion engine, means being provided to at will control such pressure and exhaust for vibration of the diaphragm of the horn.

My invention comprises novel details of improvement that will be more fully herein-after set forth and then pointed out in the claims.

Reference is to be had to the accompanying drawings, forming part hereof, wherein, Fig. 1 is a partly sectional side view of a signal horn embodying my invention;

Fig. 2 is a cross section on line 2, 2, in Fig. 1;

Fig. 3 is a section on line 3, 3 in Fig. 2;

Fig. 4 is a detail section on line 4, 4 in Fig. 1;

Figs. 4^a and 4^b are sectional details;

Fig. 5 is a sectional view of a modification;

Fig. 6 is a section on line 6, 6 in Fig. 5;

Fig. 7 is a detail section on line 7, 7 in Fig. 5.

Similar numerals of reference indicate corresponding parts in the several views.

The horn illustrated comprises a suitable casing 1 provided with a diaphragm and a sounding tube or horn 3, which may be of any suitable or usual construction. The diaphragm is shown provided with a projection 4, illustrated in the form of a screw retained in adjusted position by a nut 5. An actuator or rotor 6 is shown provided with an uneven surface or projections at 7, of any well-known variety, to engage the projection 4 to

cause vibration of the diaphragm. I provide a reciprocative member or piston 8 to operate the actuator 6, which member or piston is guided within a cylinder or tube 9 carried by casing 1 in any suitable way, as by means of bracket or block 10 secured by screws or the like to the casing and to cylinder 9.

In the form shown in Figs. 1 to 4 the actuator or rotor 6 is carried by a shaft 11 journaled in the bracket 10 and provided with a gear or pinion 12 that is in mesh with gears 13, 14 loose on shafts 15, 16 journaled in bearings on the aforesaid bracket or support. The shafts 15, 16 respectively carry ratchet wheels 17, 18 adapted to be engaged by spring pressed pawls 19, 20 pivotally carried by gears 21, 22 respectively that are in mesh with rack teeth 8^a, 8^b shown on opposite sides of the piston or member 8. The cylinder 9 is shown provided with slots 9^a in its wall through which the gears 21, 22 project to mesh with the racks 8^a, 8^b. When the piston or member 8 is reciprocated the gearing will be operated in an appropriate direction in such a manner that the gears 17, 18 will cause the dogs 19, 20 to rotate the gears 13, 14 in similar direction so that the pinion or gear 12 will be rotated in a single direction for correspondingly rotating the actuator or rotor 6 to engage the projection 4 of the diaphragm to vibrate the latter for producing a signal. It will be understood that one of the sets of gears and the corresponding ratchet, pawl and rack may be omitted, such as the parts 14, 16, 18, 20 and 22.

In the construction shown in Figs. 5 and 6 the actuator 6 is in segmental form and is rocked to operate the projection 4 of the diaphragm. In this case the actuator 6 is carried by a pivot 23 supported by bracket 10, and said actuator is provided with gear teeth 6^a projecting through slot 9^a in cylinder 9 and in mesh with rack 8^a on piston or member 8. When said piston is reciprocated the actuator 6 will be rocked to cause its projection or teeth 7 to operate projection 4 of the diaphragm to vibrate the latter. To resist the operation of the actuator and the piston at the termination of their strokes I provide cushioning means. In Fig. 5 I have illustrated springs 6^c carried by the actuator adapted to engage the

cylinder 9 near the termination of the strokes of the actuator to resiliently resist such strokes.

The piston or member 4 is to be reciprocated by means of gas pressure and exhaust from an internal combustion engine. Any suitable means may be provided to control, at will, the gas pressure and exhaust in cylinder 9. In the form shown in Figs. 1 to 4 a valve 24 is carried by a stem 25 longitudinally operative in cylinder 9, and piston or member 8 is provided with a bore 8^b through which said stem projects, whereby said piston is slideable with respect to the stem. Valve 24 is adapted to close against a seat 26 at the lower end of cylinder 9. Said cylinder may be attached to a gas engine to communicate with its cylinder by any suitable means, such as by threads or a fitting 27 on said cylinder 9, whereby the bore of said cylinder may be placed in communication with the engine cylinder, the valve 24 controlling gas pressure and exhaust from the engine cylinder to cylinder 9. The stem 25 may be operated by any suitable means. I have illustrated a lever 28 adapted to engage stem 25 to unseat the valve and a spring 29 operative against a nut or fitting 30 and against a stop 31 on stem 25 serves normally to close the valve against its seat. The lever 28 is pivotally supported upon projection 32 extending from nut 30. Lever 28 may be connected by any suitable connection with a pull button or lever that may be attached to any part of an automobile, boat or the like in convenient position to be controlled by the operator.

In the form shown in Figs. 5, 6 and 7 the cylinder 9 may be connected with any suitable support, as by means of a fitting 33 attached to cylinder 9 and adapted to be attached to a suitable support such as to a bracket carried by an automobile or boat. A pipe 34 is connected to fitting 33 and to a valve construction 35 which is adapted to be attached to the cylinder of an internal combustion engine to receive compressed gases and exhaust therefrom. The valve construction 35 comprises a casing to which the pipe 34 is connected and has a valve 36 provided with a stem 36^a to be operated by a lever 37 pivotally supported upon the casing. The valve is normally closed and when lever 37 is operated by means of a connection 38 the pressure and exhaust from the engine will operate in cylinder 9 to actuate the piston or member 8. The valve casing 35 may be connected with a spark plug or an adopter of known construction to receive pressure and exhaust from the engine.

To control the effective pressure in the bore of cylinder 9, of Figs. 5 to 7, the piston or member 8 is provided with a stem

39 depending therefrom and which may be attached to piston 8 by screw threads and a locking nut. The stem travels freely through an apertured valve seat member or disk 40 secured within the bore of cylinder 9, so that gases may pass freely around stem 15 through the bore of the disk. Opposite sides of the disk are adapted to co-operate with valves 41, 42 that are slideable freely on stem 39 on opposite sides of disk 40 to co-operate with the seats of the disk. A spring 43 on stem 39, thrusting against the piston, normally pushes valve 41 toward disk 40 and a spring 44 on said stem bearing against a stop 45 on said stem and against valve 42 normally pushes the valve toward disk 40. Shoulders 46, 47 on stem 39 resist movement of valves 41 and 42 toward disk 40. The valves 41, 42 may alternately bear against opposite sides of disk 40 and may float with stem 15 free from disk 40 for a distance of travel of piston 8. When piston 8 has risen on the pressure stroke part of its limit of travel the valve 42 will engage disk 40 to shut off flow of fluid against piston 8 and the momentum of the said member will cause it to continue a short distance against the resistance of spring 44 whereupon the piston will stop. For the next stroke suction or exhaust in the lower part of cylinder 9, as well as the effect of gravity, will cause piston 8 to descend and valve 42 will pass from disk 40, and after part of the limit of such stroke the valve 41 will engage disk 40 to shut off the effect of the exhaust in the bore of cylinder 9 against piston 8 and the momentum of said piston will be checked by spring 43 and the piston will stop.

The reciprocations of the piston or member 8 may be checked by any suitable means, such as by springs *a*, *b*, within cylinder 9, (Fig. 4^b). The controlling valve construction for the pressure and exhaust, shown in Figs. 5 to 7, may be used in the form shown in Figs. 1 to 4^a, in which case the valve 24, its stem 25 and lever 28 will be omitted.

In accordance with my invention, when the pressure and exhaust from a gas engine is effective in cylinder 9, the piston or member 8 will reciprocate to cause operation of actuator 6, either with rotary motion in one direction as in Figs. 1 to 4, or with oscillating or rocking motion as in Figs. 5 to 7, to cause vibration of the diaphragm.

Changes may be made in the detail of construction set forth, within the scope of the appended claims, without departing from the spirit of my invention.

Having now described my invention, what I claim is:—

1. A signal horn comprising a diaphragm having a projection, an actuator for the projection, a cylinder, a piston reciprocative in the cylinder, devices to operate the actua-

tor, the piston having means to operate said devices, and means to at will connect said cylinder with a source of pressure and exhaust to reciprocate said piston by alternate pressure and exhaust.

2. A signal horn comprising a diaphragm having a projection, an actuator for the projection, a cylinder, a piston reciprocative in the cylinder, gearing between the piston and the actuator for operating the latter by the former, and means to at will connect said cylinder with a source of pressure and exhaust to reciprocate said piston by alternate pressure and exhaust.

10 3. A signal horn comprising a diaphragm having a projection, an actuator for the projection, a cylinder, a piston reciprocative in the cylinder, said piston having a rack, gear means actuated by the rack to operate the actuator, a pipe communicating with the cylinder, a casing connected to the pipe and having means to connect it to an internal combustion engine cylinder, a valve for said casing to control pressure and exhaust from the engine to the first named cylinder, and means to at will actuate said valve.

20 4. A signal horn comprising a diaphragm having a projection, an actuator for the

projection, a cylinder, a piston reciprocative in the cylinder, said piston having a rack, a gear to mesh with the rack, a gear connected with the actuator, gearing comprising a ratchet operating the actuator in one direction, a pipe communicating with the cylinder, a casing connected to the pipe and having means to connect it to an internal combustion engine cylinder, a valve for said casing to control pressure and exhaust from the engine to the first named cylinder, and means to at will actuate said valve.

25 5. A signal horn comprising a diaphragm having a projection, an actuator for the projection, a cylinder a piston reciprocative in the cylinder, said piston having racks, gears in mesh with said racks, shafts provided with loose gears and having ratchets attached to the shafts, pawls carried by the last named gears and co-operative with the ratchets, a gear connected with the actuator and in mesh with the last named gears, and means to at will connect said cylinder with a source of pressure and exhaust to reciprocate said piston by alternate pressure and exhaust.

SAMUEL C. RODESS.
